Primary Examiner—Terry A. Wallace*Assistant Examiner*—Mitchell I. Siegel*Attorney, Agent, or Firm*—William W. Haefliger[57] **CLAIM**

The ornamental design for golf club head, as shown and described.

DESCRIPTION

FIG. 1 is a top front perspective view of a golf club head having a 9° incline, showing our new design;

FIG. 2 is a top plan view of the FIG. 1 head;
FIG. 3 is a front face elevation view of the FIG. 1 head;
FIG. 4 is a bottom plan view of the FIG. 1 head;
FIG. 5 is a toe end elevation view of the FIG. 1 head;
FIG. 6 is a heel end elevation view of the FIG. 1 head;
FIG. 7 is a rear elevation view of the FIG. 1 head;
FIG. 8 is a top plan view of a second embodiment of the golf club head having an 11° incline;

FIG. 9 is a front face elevational view of the FIG. 8 head;
FIG. 10 is a bottom plan view of the FIG. 8 heads;
FIG. 11 is a toe end elevational view of the FIG. 8 head;
FIG. 12 is a heel end elevational view of the FIG. 8 head;
and,
FIG. 13 is a rear elevational view of the FIG. 8 head.
